UNITED STATES PATENT OFFICE.

ARTHUR LESLIE FLOWER, OF WAKEFIELD, ENGLAND.

MACHINE FOR APPLYING PRINTED LABELS TO BOTTLES.

Application filed April 22, 1924. Serial No. 708,221.

To all whom it may concern:

Be it known that I, ARTHUR LESLIE FLOWER, a British subject, and resident of 19a Ings Road, Westgate, Wakefield, Yorkshire, England, have invented certain new and useful Improvements in Machines for Applying Printed Labels to Bottles, of which the following is a specification, such as will enable others skilled in the art to 10 which it appertains to make and use the same.

This invention relates to machines for applying printed labels to bottles and of that kind in which the labels are removable one 15 at a time from a holder for application to the bottle and in which, between the said removing and the application, they are generally supplied with an adhesive.

It is often desirable that the labels shall 20 be dated or otherwise marked with an india rubber, metal or other stamp for purpose of reference or notification at a later date and my invention is designed to enable this dating or other such marking to be easily and 25 accurately effected and with but small addition to the machine to which the invention is applied.

For this purpose it has been previously suggested to provide a pivoted lever with a 30 stamp, the lever being rocked by a moving part of the machine, the movement of the lever also serving to move an inking roller over the type. It has also been suggested to rock a type-carrying lever by means of a 35 pulley and chain, the pulley being rotated by a rack and pinion device operated by a reciprocating part of the machine, whilst the stamp was inked by a roller carried by a label-picking device.

According to the present invention the 40 dating or other stamp is pivotally mounted on a spindle at one end of a bell crank lever and on the movement of the bell crank lever is rotated on its axis from the inking position into the printing position. This movement is preferably effected by means of 45 toothed wheel gearing disposed between the spindle of the stamp and the pivot of the bell crank lever.

As above indicated the type of stamp 50 may vary but in a general way an india rubber stamp coacting with an ink pad is sufficient, the type of the stamp or the stamp itself being interchangeable at will.

I will now describe my invention with 55 reference to the accompanying drawing in

which the upper part *a* of a labelling machine is seen and is provided with a carrier *b* for the labels *c*. These labels are held down by a plate *d* on a stem *e* to which is 60 fitted a gripping device *f* having a leaf-spring *g*. These parts are substantially known.

Above the holder *b* I pivot a lever *1* the free end *2* of which is positioned above an 65 aperture *3* in the frame *a* and over a plunger *4* which is vertically reciprocated from any convenient part of the machine.

The other end of the lever is adapted at 5 to receive the upper *T* shaped end of a rod 70 *6* passing through a guide *7* on a bracket *11* on the frame *a*. The lower end of this rod is fitted to a bell-crank lever *8—9* pivoted at 10 on the bracket *11* fixed to the frame *a*. The arm *9* (which may be of double or pair 75 form) carries the stamp *12* the type *13* of which impacts against an ink pad *14* supported on bracket *11*. The stamp *12* is pivoted on spindle *15* on the arm *9* and carries a toothed wheel *16* in mesh with another 80 wheel *17* also on lever *9* which latter engages a fixed tooth segment *18*.

The action is substantially as follows:— the plunger *4* rises and strikes the end *2* of lever *1* thus depressing the other end *5* 85 and causing the rod *6* to rock the lever *8—9* from its full line position to that indicated by dotted lines immediately below the labels and brings the india rubber or other stamp against the bottom label onto which the date 90 or other matter is printed. Upon the fall of plunger *4* the lever *1* returns to the full line position shown and its movement may be assisted by a spring coiled round the pivot on which the lever *8—9* rocks or arranged in 95 some other place. As the lever *8—9* moves the wheel *17* is turned because of its engagement with the fixed sector *18* and this wheel rotates the wheel *16* and brings the stamp into its correct positions relative to the pad 100 and the labels.

Above the label holder a cover *19* is pivoted on pin at *20*. This cover carries the lever *1* and has the rod *e* passed through it. When the labels are to be replenished the 105 lever *1* and rod *6* are disconnected at *5*, the rod *e* and plate *d* are raised and the cover turned to one side thus giving free access to the interior of holder *b*.

What I claim is:—

In a bottle labelling machine, a label carrier open at the lower end, a cover for said

label carrier, a lever pivotally supported on said cover and having an operative end arranged beyond the holder, an inking pad arranged below and spaced from the holder, a stamp to cooperate with said pad, a bell crank lever pivotally supported between the pad and holder, one end of said lever carrying the stamp, means on the lever and frame of the machine to turn the stamp into opposed relatively right angle positions in the movement from the pad to the holder, and

a rod connected to said bell crank lever and having separable connection with the first mentioned lever, whereby the cover of the holder and the first mentioned lever may be readily turned from holder covering position without interfering with the normal relation of the stamp and parts connected therewith.

In testimony whereof I have signed my name to this specification.

ARTHUR LESLIE FLOWER.
